BOTTLE FILLING MACHINERY

Conrad W. Schraitle, Cleveland, Ohio, assignor
to The Bishop & Babcock Mfg. Company, Cleve-
land, Ohio, a corporation of Ohio

Application July 17, 1931, Serial No. 551,468

19 Claims. (Cl. 226—111)

This invention relates to bottle filling machines and methods and relates particularly to bottle filling machines of the type wherein a plurality of bottles continuously fed to the machine are automatically and successively filled with a beverage such as beer, carbonated syrup or the like.

My invention comprises certain features of improvement over the mechanism illustrated and described in the application of Fred W. Muller, Serial No. 497,665, filed November 24, 1930, for Bottle filling machines and methods.

The invention of the instant application relates more particularly to a valve construction particularly adapted to bottle filling machinery of the type set forth in said application. A brief reference to the machine as a whole will be made herein with a more complete description of the valve mechanism forming the subject-matter of the instant application, and for a more complete description of the machine as a whole, reference may be had to the above identified application.

In the operation of machines of this general class, a bottle to be filled with the beverage is, in the course of its path through or around the machine, elevated to a filling position at which its open mouth is sealingly pressed against a suitable beverage discharging outlet. Subsequently, a valve is automatically turned to admit beverage from a supply tank to the bottle to fill it. In the rapid operation of the machine, it sometimes happens that a bottle which has been carelessly handled and cleaned prior to the filling process, is presented to the said discharge orifice with the mouth thereof chipped or broken so that a perfect seal with the discharge orifice is not effected. As a result, when the beverage valve is opened, the beverage may flow or be discharged, not into the bottle but outwardly through the chipped portion of the bottle mouth to the atmosphere and be wasted.

It is therefore an object of this invention to provide a valve mechanism, controlling the discharge of beverage from the supply tank to the bottle, during the continuous operation of a bottle filling machine, and constructed to automatically shut off, in an improved manner, the flow of beverage when the same exceeds a predetermined rate of flow such as might be occasioned by presenting to the filling apparatus a bottle having a mouth which is broken or chipped or the like.

Another object is to provide, in a bottle filling machine, a valve mechanism having the characteristics referred to and provided with means

whereby the valve, after it has automatically shut off the flow, may automatically be restored to its discharging condition to fill the next successive bottle.

Another object is to provide a discharge flow controlling valve for bottle filling machines which will automatically, and in an improved manner, detect a bottle having a broken or chipped open mouth and which will automatically and instantaneously cut off the flow of beverage to the bottle the moment the flow thereto starts.

Another object is to provide, in a bottle filling machine of the type in which, after a bottle is presented to a discharge orifice for filling, a valve is automatically opened to admit beverage thereto, an improved means for cutting off the flow of fluid the moment it starts provided that the bottle is defective in that it has a chipped or broken mouth, and which operation of the valve to its closed position automatically restores the flow-interrupting means to a normal position where it will be inoperative for bottles which are not so defective.

Other objects will be apparent to those skilled in the art to which my invention appertains.

My invention is fully disclosed in the following description taken in connection with the accompanying drawing, in which:

Fig. 1 is a fragmentary cross-sectional view of a part of a bottle filling machine and showing an embodiment of my invention associated therewith;

Fig. 2 is a fragmentary cross-sectional view taken approximately from the plane 2 of Fig. 1;

Fig. 3 is a fragmentary view taken from the plane 3 of Fig. 1;

Fig. 4 is a view similar to Fig. 1 but illustrating a modification of my invention.

Referring to the drawing, I have shown at 1 a beverage supply tank in which a quantity of beverage to be bottled is contained. The beverage is generally of the carbonated type and gas therefrom accumulates in the upper part 2 of the tank; and to prevent its escape therefrom, the cover 3 of the tank is sealed to the tank as by a gasket 4. The beverage which only fills a part of the tank is indicated at 5.

A valve head 6 is secured to the bottom of the tank 1 and a valve device to be more fully described is disposed therein whereby a bottle 7 may be filled by beverage 5 from the tank 1.

As will be understood from the more complete description hereinbefore referred to, there may be a plurality of valve heads 6 and the valve heads and the tank 1 may rotate around a central

axis not shown, and a continuous succession of bottles 7 may be automatically moved to successively bring a bottle into association with each valve head and after operation of the valve head 5 to fill the bottle, the bottle may be removed.

The apparatus for rotating the tank and valve heads and for elevating and depressing and removing the bottle 7 has not been shown in the drawing for the sake of simplification. It may 10 be added, however, that each valve device in the valve heads 6 is provided with an external lever 8 which, during the rotation of the valve head around the central axis, engages suitably spaced and disposed fixed stops whereby as will presently 15 appear, the valve device in the head 6 will be operated successively to different positions to control the flow of beverage to the bottle 7.

The valve head 6 has sealingly fitted therein a transversely disposed valve element 9 of conical 20 form. Three passageways 10, 11 and 12 are provided therethrough diametrically disposed therein. The valve element 9 is maintained in sealed condition in the head by a spring 13 reacting against a shoulder 14 on the valve element and 25 against the sleeve 15 screw-threaded into the head 6. The valve element 9 extends outwardly through the sleeve 15 and has secured thereto the lever 8 above referred to.

When the valve element 9 is in the position illustrated, the passageway 11 establishes communication between the interior of the tank 1 and the bottle 7 by means of a duct 16 between the tank 1 and the valve element 9, and by means of a filling tube 17 extending downwardly into the bottle to a point adjacent the bottom thereof and extending upwardly out of the bottle and screw-threaded into a duct 18.

The passageway 12, with the valve element 9 in the position illustrated, establishes communication between the gas-filled space 2 above the liquid 5 in the tank 1 and the interior of the bottle 7 by means of a duct 19 in the head 6 which communicates with a pipe 20 the lower end of which is screw-threaded into the duct 19 and the upper end of which extends upwardly through the liquid 5 and into the space 2; and by means of a duct 21 in the head 6 opening into a chamber 22 and passageways 23 and 24 communicating with the chamber 22 and with 50 the interior of the bottle 7.

To effect this latter communication, the open mouth of the bottle 7 is sealed against a sealing annulus 25 and the passageway 24 opens into the interior of the annulus 25.

The passageway 24 is formed in a cylindrical head 40 by providing a coaxial bore therethrough of larger diameter than the tube 17 telescoped therethrough, and in upward movement of the bottle 7 by the parts of the filling machine not shown, the head 40 is thrust upwardly to seal the upper end thereof against a packing 41 disposed in a recess in the head 6. The packing 41 is secured in the recess by a screw-threaded gland nut 42 which presses it sealingly against a washer 43 having a central downwardly extending tubular portion 44 through which the tube 17 is telescopically disposed, and the passageway 23 extends through the tubular extension 44. Thus the passageway 23 communicates at its upper end 70 with the chamber 22 and at its lower end with the passageway 24.

In the position of the valve element 9 illustrated, the passageway 10 is in such a rotated position of the valve element that it is shut off, 75 but when the valve element 9 is rotated to a suit-

able position, the passageway 10 establishes communication between the space 2 above the liquid 5 in the tank 1 and the interior of the bottle by means of a duct 26 in the valve head and a pipe 27 the lower end of which is screw-threaded into the duct 26 and the upper end of which extends upwardly through the liquid and into the space 2 thereabove; and by means of a duct 28 in the valve head 6 which opens into the chamber 22.

Liquid 5 not only fills the tank 1 but also maintains filled at all times the duct 16. Preferably the upper end of the duct 16 is enlarged into a chamber 29 in the bottom of the tank 1. Thus a port 30 is provided at the upper end of the duct 16 where the duct joints with the chamber 29. 15 Immediately above the port 30 is a float valve 31 preferably in the form of a hollow cylinder of metal, and provided with an axially disposed stem 32 extending downwardly from the valve 31 into the duct 16 and of such length that normally the lower end thereof does not project into the passageway 11.

The valve 31 floats in the beverage in the chamber 29 and its position is maintained to maintain the stem 32 substantially axially in the duct 16, by a plurality such as three pins 33-33 disposed parallel to the axis of the cylindrical valve 31, spaced circumferentially thereabout, and secured at their upper ends to a head 34 having a body portion 35 surrounding the pipe 29 or otherwise secured thereto. The float valve 31 is prevented from floating out of the chamber 29 by engagement of its upper end with the head 34. The head 34 may be adjusted along the pipe 20 by any suitable device such as a thumb screw 36. 35

As illustrated in Fig. 2, the upper end of the passageway 11, where it terminates at the upper side of the valve element 9, is, preferably at one side of the passageway terminus, flared out or rounded over to provide a camming surface 38 40 adapted to engage and cooperate with the lower end of the stem 32 when the latter is in its downward position to be described to thrust the valve stem 32 upwardly when the valve element 9 is rotated in a manner and for a purpose to be set 45 forth later.

In the operation of my invention as thus far described, the bottle 7 is, by mechanism not shown herein but fully illustrated and described in the above-mentioned pending application, elevated to 50 the position illustrated in Fig. 1, in telescoped relation with the depending pipe 17, and with the open end or mouth of the bottle sealingly pressed against the annulus 25 and with the head 40 sealingly pressed against the packing 41. Thus 55 a passageway communication, from the chamber 22 to the interior of the bottle by way of the passageways 23 and 24, is established, sealed from the atmosphere.

The rotation of the head 6 and together therewith the bottle 7, moves the lever 8 around the central axis of the machine until it strikes a suitable stop on the machine not shown whereupon the valve element 9 is rotated to a position to align the passageway 10 with the ducts 65 26 and 28, whereupon the pressure of the gas in the part 2 of the tank 1 above the liquid, which is considerably above atmospheric pressure as is well understood, causes gas to flow downwardly through the pipe 27, through the duct 26, passageway 10, duct 28, chamber 22, passageways 23 and 24, and into the bottle 7, thus putting the interior of the bottle under the same pressure as that above the liquid 5 in the tank 1. 70

Continued movement of the rotary machine 75

subsequently gives another movement to the lever which rotates the passageway 10 out of communication with the ducts 26 and 28 and rotates the passageways 11 and 12 into the position illustrated. As will now be understood in view of the above description, the interior of the bottle now communicates with the portion 2 of the tank above the liquid 5 therein, and is therefore maintained at the pressure thereof, the communication being by way of the passageway 24, passageway 23, chamber 22, duct 21, passageway 12, duct 19 and pipe 20. Also, the filling tube 17 communicates with the liquid 5 in the tank by means of the chamber 29, duct 16, passageway 11, duct 18 and tube 17, the interior of the bottle being under pressure of the gas above the liquid in the tank, liquid will flow from the tank into the bottle through the tube 17 only by gravity and therefore with the minimum of agitation.

If, however, the mouth of the bottle 7 be chipped or broken or otherwise mutilated, the seal thereof with the annulus 25 will be destroyed, the interior of the bottle 7 will be therefore communicating with the atmosphere and be at atmospheric pressure, and liquid 5 will be forced from the tank 1 into the bottle through the tube 17 by the pressure in the part 2 above the liquid and it will tend to fill the bottle at a very rapid rate and then discharge and waste through the mutilation at the mouth of the bottle. But this is prevented by my invention as follows. The rapid high velocity rush of fluid or liquid just referred to occurring downwardly through the chamber 29 and duct 16, carries the float valve along with the liquid and seals the lower end of the valve 31 against the port 30, immediately and completely shutting off the flow of liquid. Thus only a very small quantity of liquid flows to the bottle 7 and the defective bottle proceeds around through the cycle of the filling machine without being filled and is thus clearly detectable and may be removed from the machine and discarded.

When the valve 31 has once seated on and sealed the port 30, it is held thereon by the liquid pressure above it.

After the machine as a whole has rotated to the position at which ordinarily the bottle 7 would have been filled, the lever 8 strikes another suitable stop which rotates the valve element 9 to an off position at which all of the passageways 10, 11 and 12 are sealed off. Such rotary movement of the valve element 9 may be made clockwise as viewed in Fig. 2, and will therefore move the camming surface 38 into camming engagement with the lower end of the stem 32 to effect an upward thrust on the stem to raise the valve 31 from its seat on the port 30, so that by the time the valve element 9 has turned so as to seal off the passageway 11, the valve 31 will be raised from its seat and it may float to its original or normal position illustrated in Fig. 1. The parts are now in the position for another bottle-filling operation.

As will now be well understood, the rate of flow of liquid downwardly through the duct 16 during the normal filling of a perfect bottle is not a rate of flow sufficient to draw the float valve 31 along with it to seal the port 30.

In the modification illustrated in Fig. 4, a valve 50 is illustrated which is not a float valve but which may be made of any solid material, such as metal. A stem 51 may be screw-threaded into the lower side of the valve 50 and extend downwardly into the duct 16; and the valve element 9 may

be provided with a camming surface as in Fig. 2 to cooperate therewith. The valve 50 is normally supported by a compression spring 52, the lower end of which abuts upon a shoulder 53 on a head 54 adjustably clamped longitudinally on the pipe 20 by a thumb screw 55 or like device. A stem 56 extends through a clearance bore in the head 54 and is screw-threaded into the upper side of the valve 50, extends upwardly through the compression spring 52 and has on its upper threaded end 10 an adjusting nut 57. Thus the upward thrust of the spring on the nut 57 and stem 56 supports the valve 50. The spring 52 may be a relatively delicate spring, but in any case may be adjusted to support the valve 50 against the normal flow of liquid downwardly through the duct 16 but to permit the valve 50 to be drawn downwardly by a greater than normal rate of flow such as is occasioned by a broken bottle as hereinbefore described.

My invention is not limited to the exact details of construction hereinbefore shown and described. Many changes and other modifications may be made within the scope and spirit of my invention without sacrificing its advantages.

I claim:—

1. In a bottle filling machine of the type comprising a source of liquid supply and means to move a bottle to be filled into sealed engagement with a filling device, means providing a passageway in the device from the supply source to the bottle, a valve element in the device movable to establish and to shut off respectively the flow of liquid through the passageway to the bottle, an automatic auxiliary valve element in the line of flow, adjustable stop means, resilient means for holding the auxiliary valve element open against the stop means at a predetermined maximum open position to permit said flow when below a predetermined rate and to permit it to be closed by said flow to shut off said flow when above a predetermined rate and means for moving the auxiliary valve element from closed to open position actuated by movement of the valve element from flow to shut-off position.

2. In a filling device for bottle filling machines, a passageway through the device, a valve element in the device movable to passageway open and closed positions, an auxiliary valve element normally resiliently supported in a passageway open position and movable to a passageway closing position by flow of liquid through the passageway above a predetermined rate, a movement transmitting means between the valve element and the auxiliary valve element for moving the auxiliary valve element to passageway open position by movement of the valve element to closed position, an adjustable positive stop for said auxiliary valve element at the maximum flow open position, guide means movable with said adjustable positive stop and guiding the movement of the auxiliary valve element from the maximum flow open position to the flow stop position.

3. In a filling device for bottle filling machines, means providing a passageway through the device, a rotary valve element in the device movable to passageway open and closed positions, an auxiliary valve element controlling flow through the passageway and having a passageway open position, and movable to a passageway closing position by flow of liquid through the passageway above a predetermined rate, adjustable stop means, means for holding the auxiliary valve element normally in passageway open position against the stop when the rate of flow is below

- the predetermined rate only, and a cam surface on the valve element adapted to engage a portion of the auxiliary valve element to move it toward passageway open position upon rotation of 5 the valve element to closed position, and guide means movable with the adjustable stop means and guiding the movement of the auxiliary valve element from the maximum flow open position to the flow stop position.
- 10 4. In a filling device for bottle filling machines, a passageway through the device, a rotary valve element in the device movable to passageway open and closed positions, an auxiliary valve element controlling flow through the passageway 15 having a passageway open position, and movable to a passageway closing position by flow of liquid through the passageway above a predetermined rate, maximum flow stop means for the auxiliary valve element, means for holding the auxiliary valve element normally in passageway open position against the stop when the rate of flow is below the predetermined rate only, and a movement transmitting means between the valve element and the auxiliary valve element for moving the 20 auxiliary valve element to passageway open position by movement of the valve element to closed position.
- 15 5. In a filling device for bottle filling machines, means providing a passageway through the device, a rotary valve element in the device movable to passageway open and closed positions, an auxiliary valve element controlling flow through the passageway having a passageway open position, and movable to a passageway closing position 25 by flow of liquid through the passageway above a predetermined rate, a stop, means for holding the auxiliary valve element normally in passageway open position against the stop when the rate of flow is below the predetermined rate only, movement transmitting means between the valve element and the auxiliary valve element for moving the auxiliary valve element to passageway open position by movement of the valve element to closed position.
- 30 6. In a filling device for bottle filling machines, means providing a passageway through the device, a rotary valve element in the device movable to passageway open and closed positions, an auxiliary valve element controlling flow through the passageway having a passageway open position, and movable to a passageway closing position 35 by flow of liquid through the passageway above a predetermined rate, adjustable stop means, adjustable means for holding the auxiliary valve element normally in passageway open position against the stop when the rate of flow is below the predetermined rate only, and a movement transmitting means between the valve element and the auxiliary valve element for moving the auxiliary valve element from the maximum flow open position to the flow stop position.
- 35 7. In a filling device for bottle filling machines, comprising a supply tank and a vertically disposed conduit extending from the tank bottom, means providing a passageway through the device, a valve element in the device movable to passageway open and closed positions, an auxiliary valve element normally supported in a passageway open position by liquid flowing through the passageway and occupying a predetermined stop maximum flow open position and 40 movable to a passageway closing position by flow of liquid through the passageway above a predetermined rate, a stop adjustably supported by the conduit for predetermining the maximum flow position of the auxiliary valve element, and movement transmitting means between the valve element and the auxiliary valve element for moving the auxiliary valve element to passageway open position by movement of the valve element to closed position.
- 45 8. In a filling device for bottle filling machines comprising a supply tank and a vertically disposed conduit extending from the tank bottom, a valve element in the device movable to passageway open and closed positions, an auxiliary valve element normally supported in a passageway open position and movable to a passageway closed position by flow of fluid through the passageway above a predetermined rate, a manually adjustable stop movable along the conduit and engageable with the auxiliary valve element to predetermine the maximum flow open position, and movement transmitting means between the valve element and the auxiliary valve element for moving the auxiliary valve element to passageway open position by movement of the valve element to closed position.
- 50 9. In a filling device for bottle filling machines comprising a supply tank and a vertically disposed conduit extending from the tank bottom, means providing a passageway through the device, a valve element in the device movable to passageway open and closed positions, an auxiliary float valve element controlling flow through the passageway normally floating in liquid flowing through the passageway and occupying a predetermined stop maximum flow open position and movable to a passageway closing position by flow of liquid through the passageway above a predetermined rate, an adjustable stop supported by the conduit limiting the buoyant upward movement of the auxiliary valve element to predetermine the maximum flow open position, and movement transmitting means between the valve element and the auxiliary valve element for moving the auxiliary valve element to passageway open position by movement of the valve element to closed position.
- 55 10. In a filling device for bottle filling machines comprising a supply tank and a vertically disposed conduit extending from the tank bottom, means providing a passageway through the device, a valve element in the device movable to passageway open and closed positions, an auxiliary valve element controlling flow through the passageway, an adjustable member movable along the conduit resiliently supporting the auxiliary element whereby the auxiliary element is movable to a predetermined stop maximum flow position under the joint influence of the resilient support and liquid flowing through the passageway, and movable to a passageway closing position by flow of liquid through the passageway above a predetermined rate, and movement transmitting means between the valve element and the auxiliary valve element for moving the auxiliary valve element to passageway open position by movement of the valve element to closed position.
- 60 11. In a filling device for bottle filling machines, a passageway through the device, a valve element in the device movable to passageway open and closed positions, an auxiliary valve element normally resiliently supported in a passageway open position and movable to a passageway clos- 65
- 65 70 75

ing position by flow of liquid through the passageway above a predetermined rate, an adjustable positive stop for said auxiliary valve element at the maximum flow open position, guide means movable with said adjustable positive stop and guiding the movement of the auxiliary valve element from the maximum flow open position to the flow stop position.

12. In a filling device for bottle filling machines, a passageway through the device, a rotary valve element in the device movable to passageway open and closed positions, an auxiliary valve element controlling flow through the passageway having a passageway open position, and movable to a passageway closing position by flow of liquid through the passageway above a predetermined rate, maximum flow stop means for the auxiliary valve element, means for holding the auxiliary valve element normally in passageway open position against the stop when the rate of flow is below the predetermined rate only.

13. In a filling device for bottle filling machines, means providing a passageway through the device, a rotary valve element in the device movable to passageway open and closed positions, an auxiliary valve element controlling flow through the passageway having a passageway open position, and movable to a passageway closing position by flow of liquid through the passageway above a predetermined rate, a stop, means for holding the auxiliary valve element normally in passageway open position against the stop when the rate of flow is below the predetermined rate only, and guide means guiding the movement of the auxiliary valve element from the maximum flow open position to the flow stop position.

14. In a filling device for bottle filling machines, means providing a passageway through the device, a rotary valve element in the device movable to passageway open and closed positions, an auxiliary valve element controlling flow through the passageway having a passageway open position, and movable to a passageway closing position by flow of liquid through the passageway above a predetermined rate, adjustable stop means, adjustable means for holding the auxiliary valve element normally in passageway open position against the stop when the rate of flow is below the variable predetermined rate only.

15. In a filling device for bottle filling machines, comprising a supply tank and a vertically disposed conduit extending from the tank bottom, means providing a passageway through the device, a valve element in the device movable to passageway open and closed positions, an auxiliary valve element normally supported in a passageway open position by liquid flowing through the passageway and occupying a predetermined stop maximum flow open position and movable to a passageway closing position by flow of liquid through the passageway above a predetermined

rate, a stop adjustably supported by the conduit for predetermining the maximum flow position of the auxiliary valve element.

16. In a filling device for bottle filling machines comprising a supply tank and a vertically disposed conduit extending from the tank bottom, a valve element in the device movable to passageway open and closed positions, an auxiliary valve element normally supported in a passageway open position and movable to a passageway closed position by flow of fluid through the passageway above a predetermined rate, a manually adjustable stop movable along the conduit and engageable with the auxiliary valve element to predetermine the maximum flow open position.

17. In a filling device for bottle filling machines comprising a supply tank and a vertically disposed conduit extending from the tank bottom, means providing a passageway through the device, a valve element in the device movable to passageway open and closed positions, an auxiliary float valve element controlling flow through the passageway normally floating in liquid flowing through the passageway and occupying a predetermined stop maximum flow open position and movable to a passageway closing position by flow of liquid through the passageway above a predetermined rate, an adjustable stop supported by the conduit limiting the buoyant upward movement of the auxiliary valve element to predetermine the maximum flow open position.

18. In a filling device for bottle filling machines comprising a supply tank and a vertically disposed conduit extending from the tank bottom, means providing a passageway through the device, a valve element in the device movable to passageway open and closed positions, an auxiliary valve element controlling flow through the passageway, an adjustable member movable along the conduit resiliently supporting the auxiliary element whereby the auxiliary element is movable to a predetermined stop maximum flow position under the joint influence of the resilient support and liquid flowing through the passageway, and movable to a passageway closing position by flow of liquid through the passageway above a predetermined rate.

19. In a bottle filling machine of the type comprising a source of liquid supply and means to move a bottle to be filled into sealed engagement with a filling device, means providing a passageway in the device from the supply source to the bottle, a valve element in the device movable to establish and to shut off respectively the flow of liquid through the passageway to the bottle, an automatic auxiliary valve element in the line of flow, adjustable stop means, resilient means for holding the auxiliary valve element open against the stop means at a predetermined maximum open position to permit said flow when below a predetermined rate and to permit it to be closed by said flow to shut off said flow when above a predetermined rate.

CONRAD W. SCHRAITLE.
